UNITED STATES PATENT OFFICE.

CHARLES B. SCHILLING, OF CHICAGO, ILLINOIS.

WINDOW FRAME AND SASH.

SPECIFICATION forming part of Letters Patent No. 738,491, dated September 8, 1903.

Application filed October 6, 1902. Serial No. 126,104. (No model.)

To all whom it may concern:

Be it known that I, CHARLES B. SCHILLING, a citizen of the United States of America, and a resident of Chicago, in the county of Cook and State of Illinois, have invented certain new and useful Improvements in Window Frames and Sashes, of which the following is a specification.

The main objects of my invention are to provide an improved form of fireproof window frame and sash, to provide an improved form of swinging sash having suitable means for securing same into a plurality of different positions, to provide improved means for automatically locking same in its closed position, and to provide improved means for causing the closing of the sash in cases of fire in the immediate vicinity of same. I accomplish these objects by the device shown in the accompanying drawings, in which—

Figure 1 is an elevation of a window frame and sash constructed according to my invention, showing same in its closed position, as seen from the interior of the building. Fig. 2 is a vertical section along the line 2 2 of Fig. 1, showing the upper sash swung to an open position. Fig. 3 is a horizontal section, partly broken away, along the line 3 3 of Fig. 1. Fig. 4 is a horizontal section, partly broken away, along the line 4 4 of Fig. 1. Fig. 5 is an elevation of one of the bracket-plates by means of which the sash is pivotally connected to the frame. Fig. 6 is a side elevation of the latch which serves to hold the sash in its closed position.

The device shown consists of a sheet-metal window-frame 5, having a permanently-closed window 6 in the lower part of same and having a swinging sash 7 pivotally mounted in the upper part of same. The frame 5 is rectangular, and its bars are constructed of sheet metal. Each of the side bars 8 of the frame 5 is provided with a groove 9, which extends vertically along its inner face throughout its entire length. A cross-bar 10 extends transversely between the inner faces of the bars 8 and is rigidly secured to said bars. The bar 10 is preferably made of the shape shown, providing a shoulder 11, which serves as a stop for the lower part of the sash 7 and having in its under side a groove 12, which extends along the entire length of the bar 10. The bottom

bar 13 or sill of the sash is provided with a groove 14, corresponding in location to the groove 12 of the cross-bar 10. The groove 9 in each of the frame-bars 8 and below the cross-bar 10 is filled by a sash-bar 15, the transverse section of which is best shown in Fig. 4. The bar 15 consists of a piece of sheet metal bent to a channel-shaped section, as shown, and bent upon itself to form a flange 16, which serves as a stop extending along one edge of one face of the window-pane 17. The pane 17 is seated in the grooves 12 and 14 of the frame 5 and is confined against the stop 16 by means of strips 18, which are removably secured to the bars 15, as shown.

The sash 7 loosely fits the upper opening of the frame 5 and is pivotally secured to the side bars 8 of said frame by means of the pins 19, which are rigidly secured to the bars 8. Reinforcing-plates 20 afford the required local strength. The side bars of the sash 7 are preferably constructed of two parts—the main part 21 and the member 22, which is slidably secured to the part 21 by having its curled edges 23 engaged by the curled edges 24 to the part 21. Each of the members 22 has rigidly secured thereto, at a point slightly above the middle of same, a plate 25, which is provided with a suitable aperture 26 for engaging the pivot 19. The plate 25 is also provided with a flange 27, which extends along the face 28 and is secured thereto by means of screws 29, which are tapped into a reinforcing-strip 30, suitably located on the interior of the face 28.

The groove 9 in the bar 8 of the frame 5 and adjacent to the sash 7 is filled by a bar 31, which is constructed of sheet metal and is bent upon itself to form the flanges 32 and 33, which serve as stops to the sash 7 when same is in its closed position. The flange 32 extends along one side of the bar 9 from the upper end of same to a point 34, near the pivot 19. Similarly the flange 33 extends along the other side of the bar 9 from its lower end upwardly to a point near the pivot 19.

The lower bar 35 of the sash 7 is provided with a catch which is adapted to lock said sash in its closed position. Said catch consists of a bracket 36, to which a latch 37 is pivotally secured. The latch 37 is weighted, so as to normally assume the position shown by the

dotted lines 37', which corresponds to that shown at 37" when the sash is closed. To prevent the latch 37 from falling below the position 37', said latch is provided with a shoulder 38, which engages the bar 35 and limits the movement of said latch. The latch 37 is also provided with a hook or shoulder 39, which engages the face 40 of the bar 10 and secures the sash 7 in its closed position. The surface 41, which is in advance of the shoulder 39, is suitably curved to cause the raising of the latch 37 when brought into engagement with the upper edge of the shoulder 11 on the cross-bar 10 of the frame 5. A chain 42 passes over the sheave 43 at the upper end of the sash 7 and has one end secured to an eye 44 in the latch 37. The other end of the chain 42 is provided with a plurality of large links 45, which are adapted to engage a hook 46 on the sill 13 of the frame 5. The sheave 43 is journaled upon a pin 47, which is secured by means of a suitable bracket 48 to the top bar 49 of the sash 7. The pin 47 is preferably constructed of fusible material and is adapted to fall and release the chain 42 when subjected to a certain high temperature, such as would occur in the case of fire near said sash.

The operation of the device shown is as follows: During the construction of the device the various parts of the frame 5 are assembled in their respective positions, as shown in Figs. 1 and 2. The sash-bars 15 are then placed in the grooves 9 below the cross-bar 12. The pane of glass 17 is inserted into the groove 12 and moved upward into same until its lower edge may pass into the groove 14 in the sill 13. The pane 17 is then lowered to the bottom of the groove 14 and is securely clamped against the flanges 16 by means of the fastening-strips 18, which are securely screwed to the adjacent bars 15. The bars 31 are now placed within the grooves 9 and above the cross-bar 10. The plates 25 are now securely riveted to the members 22, and the members 22 are slid into their approximate position with respect to the parts 21 of the sash 7. The sash 7 is now placed in position between the bars 31 and secured in such position by means of the pivots 19. The members 22 may now be shifted slightly longitudinally of the parts 21 of the sash 7 until said sash will turn freely upon the pivots 19 and properly fit between the bars 31. The flanges 27 of the plates 25 are now secured to the adjacent parts of the shaft by means of the screws 29. These screws securely fasten the members 22 against further movement longitudinally of the parts 21. This adjustment of the members 22 with respect to the parts 21 simplifies the work of perfecting the alinement of the pivots 19 and the fit of the sash within the frame during construction. When it is desired to open the upper sash, it is only necessary to pull upon the chain 42, and thereby lift the latch 37. Continued pull upon the chain 42 tends to pull the upper end of the

sash outward from the frame, as shown in Fig. 2. The sash may be secured in any of its open positions by passing one of the links 45 over the hook 46. If the chain 42 is now released from the hook 46, the weight of the sash will cause same to close, and the weight of the latch 37 will cause the same to fall to its lowest position, and thereby secure the sash 7 in its closed position, as indicated by the dotted lines and marked with reference-numerals having double accents in Fig. 2. In case of fire near the sash 7 when same is in its open position the pin 47 will melt and fall under the strain upon the chain 42, and will thus release the sash and permit same to assume its closed position.

It will be seen that numerous details of the construction shown may be altered without departing from the spirit of my invention. I therefore do not confine myself to such details except as hereinafter limited in the claims.

What I claim as my invention, and desire to secure by Letters Patent, is—

1. The combination of a window frame; a sash pivoted on a horizontal axis in said frame and normally urged into a closed position; a catch movably mounted on said sash and adapted to lock same in its closed position, said catch being normally urged into locking position; a sheave journaled near the upper part of said sash; a chain passing over said sheave and having one end secured to said catch; and means for adjustably securing the free part of said chain to said sash, substantially as and for the purpose specified.

2. The combination of a window-frame; a sash pivoted on a horizontal axis in said frame and normally urged into a closed position; a catch movably mounted on said sash and adapted to lock same in its closed position, said catch being normally urged into locking position; a fusible pin secured to said sash near the upper part of same; a sheave journaled on said pin; a chain passing over said sheave and having one end secured to said catch; and means for adjustably securing the free part of said chain to said sash, substantially as and for the purpose specified.

3. The combination of a window-frame having a groove extending vertically along the inner face of each side of same; a bar fitting each of said grooves; a sash pivoted on a horizontal axis within said frame and between said bars; means for securing said sash in a plurality of different positions; each of said bars being provided with a projecting flange extending along one side of said sash when same is in its closed position from the upper part of said sash to a point near said pivotal axis, and each of said bars having a corresponding flange extending along the opposite side of said sash from the lower end of same to a point near said pivotal axis, said flanges being adapted to serve as stops for said sash, substantially as and for the purpose specified.

4. The combination of a window-frame, a

- sheet-metal sash fitting within said frame, each of the side bars of said sash having a member adjacent to the frame and longitudinally adjustable with respect to said bar; a 5 plate secured to each of said members and pivotally connected to said frame; a stop secured to said frame and extending along each edge of one face of said sash from one end of same and toward said pivotal connection; a second stop extending along the edges of the opposite face of said sash from the opposite end of same and toward said pivotal connection; said plates being of sufficient length to fill the space between the adjacent side bars 15 and frame, in the interval between the stops, and having thereon a flange extending along one face of the side bar, substantially as and for the purpose specified.
5. The combination of a window-frame, 20 having a groove extending along the inner face of each of two opposite sides of same; a bar fitting each of said grooves; a sash pivotally mounted between said bars on an axis transverse to same; each of said bars being 25 formed of sheet metal bent upon itself to form two flanges forming stops for the sash when same is in its closed position, one of said flanges extending along the edge of one face of said sash from one end of same and toward 30 the pivotal axis, and the other flange extending along the opposite face of the sash from the opposite end of same and toward the pivotal axis, substantially as described.
6. A sheet-metal window frame and sash, 35 comprising a pair of side bars, a top bar, and
- a bottom bar rigidly secured together, each of said side bars having a groove extending along its inner face and throughout its entire length; a cross-bar rigidly secured to both of said side bars at a point between the top and bottom bars and dividing said frame into two panels; a swinging sash pivotally mounted in one of said panels; each of the grooves in said side bars having a bar seated therein, in the panel which contains said swinging sash, said 40 bar being formed of sheet metal bent upon itself to form two flanges forming stops for the sash when same is in its closed position, one of said flanges extending along one edge of one face of said sash from one end of same and toward the pivotal axis, and the other flange extending along the opposite face of the sash from the opposite end of same and toward the pivotal axis; a pane of glass mounted in the second panel in said frame; a sash-bar seated in each of the grooves in the side bars of the frame, said sash-bar being formed of sheet metal bent upon itself to form a flange bearing on one face of said pane and along one edge of same; and suitable removable fastening-strips secured to said frame and adapted to hold said pane against said flanges, substantially as described.

Signed at Chicago this 1st day of October, 1902.
